UNITED STATES PATENT OFFICE.

JOHN N. QUINN, OF CINCINNATI, OHIO.

DESIGN FOR A BRICK.

SPECIFICATION forming part of Design No. 32,097, dated January 9, 1900.

Application filed November 15, 1899. Serial No. 737,145. Term of patent 14 years.

To all whom it may concern:

Be it known that I, JOHN N. QUINN, a citizen of the United States, and a resident of Cincinnati, in the county of Hamilton and State of Ohio, have invented and produced a new and original Design for Fire-Bricks, of which the following is a specification.

Figure 1 is a perspective view of a brick embodying my invention. Fig. 2 is a front view of the same. Fig. 3 is an end elevation of the same.

The principal feature of my design consists in the top and bottom faces A and B, respectively, of the brick, which are formed in parallel planes, which make an acute angle with the planes of the front and back faces C and D, respectively. The end faces E and E' have

grooves or channels e e' formed in them parallel to the top and bottom faces of the brick. The upper parts e^2 and e^3 of the end faces E and E' are cut away above the channels so as to lie in planes back of those of the lower parts e^4 and e^5 .

Another feature of my design consists in making the thickness of the brick small in comparison to its other dimensions.

What I claim is—

The design for a brick, substantially as shown and described.

JOHN N. QUINN.
